UNITED STATES PATENT OFFICE

142,418

DESIGN FOR A PORTABLE BARBECUE OR SIMILAR ARTICLE

George W. Jones, Van Nuys, Calif., assignor to A. C. Mfg. Co., Van Nuys, Calif., a corporation
of California

Application March 5, 1945, Serial No. 118,278

Term of patent 14 years

(Cl. D81—10)

To all whom it may concern:

Be it known that I, George W. Jones, a citizen of the United States, residing at Van Nuys, in the county of Los Angeles and State of California, have invented a new, original, and ornamental
Design for Portable Barbecue or Similar Article, of which the following is a specification, reference
being had to the accompanying drawing, forming a part thereof.

The figure is a perspective view showing the top, front, and one end of a portable barbecue or similar article embodying my new design.

The back and end of the portable barbecue opposite that shown in the figure both are substantially plain.

I claim:

The ornamental design for a portable barbecue
or similar article, substantially as shown and described.

GEORGE W. JONES.
